UNITED STATES PATENT OFFICE.

DAVID HENRY ELKINS, OF AMESBURY, MASSACHUSETTS.

DESIGN FOR AN AUTOMOBILE-LAMP.

49,298.

Specification for Design.

Patented July 4, 1916.

Application filed May 9, 1916. Serial No. 96,450. Term of patent 7 years.

To all whom it may concern:

Be it known that I, DAVID HENRY ELKINS, a citizen of the United States, and resident of Amesbury, in the county of Essex and State of Massachusetts, have invented a new, original, and ornamental Design for Automobile-Lamps, of which the following is a specification.

Figure 1 is a front view of a lamp embodying the new design. Fig. 2 is a view in

side elevation of the same. Fig. 3 is a view in top plan. Fig. 4 is a view in bottom plan.

I claim:

The ornamental design for an automobile lamp, as shown.

Signed at Amesbury in the county of Essex and State of Massachusetts this first day of May A. D. 1916.

DAVID HENRY ELKINS.
